CLAIM

The ornamental design for a tread portion of an automobile tire, as shown and described.

DESCRIPTION

FIG. 1 is a perspective view of the tread portion of an automobile tire according to my design;

FIG. 2 is a front view thereof;

FIG. 3 is a plane view thereof;

FIG. 4 is a right side view thereof;

FIG. 5 is a fragmentary enlarged view showing the details of the tread portion thereof;

FIG. 6 is an end view taken along line 6-6 in FIG. 5 thereof; and,

FIG. 7 is an end view taken along line 7-7 in FIG. 5 thereof. Broken lines in the drawing figures are used to show portions of the tire that are not being claimed, and thus form no part of the claimed design.
